UNITED STATES PATENT OFFICE

2,048,189

EXTENSION ROOF BOARD

William Levy, Edgewood, R. I., assignor to Moulton Ladder Manufacturing Company, Somerville, Mass.

Application May 17, 1934, Serial No. 726,093

2 Claims. (Cl. 248—237)

This invention relates to scaffolding and is herein illustrated as embodied in a portable support for swing stages.

In connection with the painting of some types of buildings, use is commonly made of scaffolding, such as a swing stage, which is designed to be suspended from the roof of a building. Some constructions heretofore employed have been suspended directly from the gutters of buildings, but the gutters are not always designed to withstand such extra weight with the result that accidents due to their giving away have occurred, leading in some localities to the passage of regulations which operate to restrict or to prevent the supporting of scaffolding from gutters. In view of the foregoing, it is an object of the present invention to provide an improved support for swing stages which can readily be secured to the ridge-pole of a building, which is adjustable to the roofs of different pitches or spans, and which at the same time will occupy a minimum of space when not in use. To this end, I have provided an extensible roof-board comprising two members in slideable engagement with each other, one of said members being provided with a hook for engaging a portion of a building and the other member being provided with means arranged to be engaged by a portion of a swing stage, together with devices for locking the members together selectively in various positions of adjustment relatively to each other. This construction provides a swing stage support which normally occupies a small space but which is readily extensible to span the distance between the ridge-pole and the eaves or gutters of a building and from which a swing stage can be suspended without placing any strain upon the gutters.

Other objects and features of the invention will be apparent from the following detailed description when taken in connection with the accompanying drawing and will be pointed out in the claims.

In the drawing,—

Fig. 1 is a perspective view of a roof-board constructed in accordance with one embodiment of my invention;

Fig. 2 is a cross-section taken along lines II—II of Fig. 1; and—

Fig. 3 is a diagrammatic view illustrating one way of utilizing the roof-board as a support for a swing stage.

As shown in Fig. 1, the roof-board comprises two boards 10 and 12 positioned with their side edges abutting each other and secured together 55 for sliding movement relatively to each other by

means of metal straps 14, 16, 18, and 20. As shown in Fig. 2, the strap 16 extends along the underside of the board 10 across the board 12 and has a hook portion 22 extending over the upper edge of the board 12. The strap 20 extends along the upper face of the board 10 and has an upwardly and laterally extending portion 24 which overlaps the edge of the board 12. The strap 16 and the strap 20 are rigidly secured to the board 10 by rivets 26. The strap 14 and the strap 18 are arranged similarly but are secured to the board 12 by rivets 28 and have portions extending over the edges of the upper face of the board 10. This construction is such that the boards 10 and 12 are held together, but with sufficient play between them and the straps that the boards are freely slideable relatively to each other.

In order that the boards 10 and 12 can be rigidly secured together in adjusted position, I provide at equally spaced intervals along the upper face of the board 10 a plurality of hard-wood blocks 30, 32 and 34 secured to the board by bolts 35 and similar blocks 36, 38 and 40 upon the upper face of the board 12. These blocks are so arranged along the faces of the boards that when the boards are adjusted relatively to each other to increase the effective length of the device one or more pairs of blocks can be brought into lateral alignment and can be locked together by means of U-shaped members 42, each of which is pivotally secured to one of the blocks by a pin 46, and is arranged to be swung into position to embrace an adjacent block on the other board. Only three pairs of blocks have been shown, but obviously a greater number can be used advantageously with long boards to give a greater number of possible variations in the length of the device.

The blocks have grooves or slots 48 to permit the passage of the hook portions 22 of the straps 14 and 16 and slots 50 to permit the passage of the ends 24 of the straps 20 upon relative sliding movement of the boards. The construction above outlined provides for the adjustment of the boards 10 and 12 relatively to each other so that the effective length of the roof-board can be varied to correspond to roofs of different pitches and spans, and also provides for locking together the two boards securely in adjusted position.

The extreme end of the board 10 has a hook member 52 which is secured thereto by rivets 54, there being a rivet 55 further to strengthen the end of the board. The hook member 52 is adapted to be placed over the ridge-pole of a

building from which a swing stage is to be hung, and the block 40 at the opposite end of the board 12 serves as an abutment from which the stage can be supported.

5 In the use of the device, as shown in the diagrammatic view in Fig. 3, two roof-boards 56 are hooked over the ridge-pole 58 of a building 60 and the effective length of each of the roof-boards is adjusted as above described so that 10 the lower end of each board 12 is adjacent to the eaves 62 of the building. A stage such as swing stage 64 can then be supported from the two roof-boards by means of hooks 66 which are hung from the blocks 40.

15 When the roof-board is not in use the boards 10 and 12 are adjusted relatively to each other until the block 34 is opposite the block 40 and the clamps 42 lock the boards in this position in which the length of the device is a minimum.

20 Thus it will be apparent that I have provided a readily adjustable portable roof-board which can be carried in a small space and which is adapted to support scaffolding without placing any strain upon gutters of a building.

25 Having described my invention, what I claim as new and desire to secure by Letters Patent of the United States is:

1. A support for swing stages comprising two

boards arranged side by side, a guide member secured to one of the boards and engaging portions of the other board for maintaining the side edges of the boards in engagement with each other during longitudinal movements of the 5 boards relatively to each other, a series of blocks on the face of one of the boards, and a U-shaped member pivotally mounted upon the face of the other board for movement laterally across the faces of the boards into position to embrace 10 a selected block of the series of blocks for securing the boards together in adjusted position.

2. A support for swing stages comprising two boards abutting each other along side edge portions thereof, means for holding the boards together for sliding movement relatively to each other comprising two straps secured to opposite faces of one of the boards the straps having end portions extending over opposite edges of a face of the other board, a plurality of spaced blocks 20 carried by each of the boards, said blocks having grooves along their sides to provide for the passage of the end portions of the straps during relative movement of the boards, a roof-hook secured to an end of one of the boards, and means 25 for clamping two of the blocks together for holding the boards in adjusted relation.

WILLIAM LEVY.
